Primary Examiner—Holly H. Baynham*(74) Attorney, Agent, or Firm*—Jeffrey D. Peterson; Michael Best & Friedrich LLP**CLAIM**

The ornamental design for a w foot anchor, as shown and described.

DESCRIPTION

FIG. 1 is a top view of the w foot anchor.

FIG. 2 is a side view of the w foot anchor; and,

FIG. 3 is a perspective view of the w foot anchor.

The present application is directed to the design illustrated in the drawings.

The broken line portions of the disclosure are for illustrative purposes only and form no part of the claimed design.
